UNITED STATES PATENT OFFICE.

TEODOR REMUS, OF DRESDEN, GERMANY.

METHOD FOR PRODUCING FOLDS FOR HOLDING THE TOP OR BOTTOM PIECES OF CARD AND PASTE BOARD BOXES IN POSITION.

No. 893,654.

Specification of Letters Patent. Patented July 21, 1908.

Application filed June 25, 1907. Serial No. 380,764.

To all whom it may concern:

Be it known that I, TEODOR REMUS, a subject of the German Emperor, residing at Blasewitzerstrasse 21, Dresden, in the Kingdom of Saxony and Empire of Germany, factory director, have invented new and useful Improvements in the Methods for Producing Folds for Holding the Top or Bottom Pieces of Card and Paste Board Boxes in Position, of which the following is a specification.

The usual known methods for manufacturing paste or card-board boxes whose top or bottom pieces, or both, are deposited in and held in position by a fold (as shown in Figure 1) overlapping the edge, are possessed of a serious defect which consists of minute, fine creases at the edge of the afore-mentioned parts. They are especially pronounced on light-colored card-boards and constitute a serious imperfection.

This invention effectively remedies this defect.

The new method is illustrated in the accompanying drawings wherein—

Fig. 1, is a section of a completed box. Fig. 2, is a section of a disk which may constitute either the top or bottom of a box.

Fig. 3, is a section of the disk when bowed to decrease its diameter. Fig. 4, is a section of a box body blank which constitutes the walls of the box or of its cover. Fig. 5, is a section of a mold with the box body blank and bowed disk inserted. Fig. 6, illustrates the flattening and consequent diametrical expansion of the disk which effects the formation of a fold in the box body.

The flat disk *a*, has a diameter greater than that of the interior of the box body *b*, to an extent double the depth of the fold. By curving or bowing the disk *a*, its diameter is decreased to such extent that it coincides with the interior diameter of the box body.

The height of the box body blank is sufficient to allow for the formation of the fold

and to give the desired height to the finished box. The connection of the disk and the body is best effected with the aid of a special mold *d*, which closely envelops the body except where the fold is to be formed, and there it is enlarged as shown. The core or block *e*, is of a diameter equal to fit the box body, and its upper face determines the elevation or height of the disk. When the body *b* has been deposited in the mold, the curved or convex disk with its convex surface turned upwards, is placed upon the core or block, and within the body, as shown in Fig. 5. By then pressing upon the bowed disk, by means of a stamp or die, it assumes its original flat shape and regains its former diameter. During the pressing of the disk *a*, the body blank where touched by the disk, is forced outwards, and the disk forms a groove in which it securely rests, as shown in Fig. 6. By then forcibly pressing or squeezing the margins of this groove against the disk *a*, a fold, as shown in Fig. 1, is completely formed. This fold extends around the edge of the disk and firmly unites the disk to the box body. The fold, thus produced, is caused by stretching the body, which obviates the possibility of the formation of creases, however fine or minute.

I claim:

The method for making card or paste-board boxes whose top or bottom piece is held in position by means of folds in the box body, consisting in bowing a disk, thereby decreasing its diameter; then inserting the bowed disk within a body blank; then flattening the bowed disk thereby forming a groove in the body blank; and finally pressing the margins of said groove to complete the fold in the box body around the edge of the disk.

TEODOR REMUS.
